Patented Aug. 10, 1976

240,931

HEATING STOVE

Gerrit Jan Faber, Leeuwarden, Netherlands, assignor to
Faber B.V., Leeuwarden, Netherlands

Filed Apr. 24, 1975, Ser. No. 571,240

Term of patent 14 years

Int. Cl. D23—03

U.S. Cl. D23—105

FIG. 1

FIG. 2

FIG. 3

FIG. 4

FIG. 5

FIG. 6

FIG. 1 is a front elevational view of a heating stove showing my new design;

FIG. 2 is a rear elevational view thereof;

FIG. 3 is a side elevational view taken from the right of FIG. 1;

FIG. 4 is a side elevational view taken from the left of FIG. 1;

FIG. 5 is a top plan view thereof;

FIG. 6 is a bottom plan view thereof.

I claim:

The ornamental design for a heating stove, substantially as shown and described.
